AIR CLEANER

Clayton C. Harrah, Niles, Mich., assignor to National Standard Company, Niles, Mich., a corporation of Michigan

Application April 3, 1935, Serial No. 14,400

6 Claims. (Cl. 183—73)

This invention relates to air cleaners, for automobile engines and the like, and is illustrated as embodied in an air cleaner having a zone of novel cleaner material in the path of the air. The invention has to do mainly with this novel material, and its construction and arrangement.

An object of the invention is to provide an inexpensive cleaner material which is effective and light in weight and which does not substantially restrict the flow of air.

One desirable type of material having these qualities is formed by making up a sheet of expanded metal and arranging it, for example by folding it upon itself in several thicknesses, to provide a series of tortuous passages for the air. I prefer to arrange the folds with the openings through the sheet out of register, either by arranging the folds to secure that effect, or by making the series of openings at an acute angle to the length of the sheet, instead of having them extend straight across.

I prefer to roll or otherwise form the interconnected strands of flat material, which surround the openings, at an acute angle (e. g. about 30°) to the plane of the sheet, so that when the sheet is folded as described above the air currents are caused to sweep across the surfaces of the strand as they pass through the described tortuous passages.

One great advantage of this material is its resilient resistance to compression crosswise of the sheet, so that a cartridge or cleaner element formed from it, made a little wider than the space containing it in the cleaner body, holds itself yieldingly and effectively sealed at its ends.

The above and other objects and features of the invention, including various novel combinations of parts and desirable particular constructions, will be apparent from the following description of the illustrative embodiment shown in the accompanying drawing, in which:

Figure 1 is a view of an air cleaner having the above-described novel cleaner material, the left half being in central vertical section and the right half in side elevation;

Figure 2 is a plan view of a sheet of metal as it is being slit, preparatory to the expanding operation;

Figure 3 is a partial plan view after expanding 50 the sheet;

Figure 4 is a section through the sheet as it is being folded;

Figure 5 is a plan view of the folded sheet, showing the arrangement of the openings out of 55 registry with each other;

Figure 6 is an enlarged partial section on the line 6—6 of Figure 5, showing the tortuous passages for the air;

Figure 7 is a plan view of a sheet in which the slits are made at an acute angle to the length of the sheet, so that most of the openings will be out of registry no matter how the sheet is folded; and

Figure 8 is a plan view of the material of Figure 7 after it is expanded and folded.

The cleaner shown in Figure 1, except for the novel structure and arrangement of the cleaner material described below, is in a general way of standard construction. It is built up of sheet metal stampings, arranged to quiet the noise of 15 the air currents passing through it, as well as to clean the air.

An upper annular stamping 10 is formed with a series of air intake openings 12, behind which a zone 14 of the described novel cleaner material 20 is arranged. It has a cover 16 held by means such as a bolt 18 and wing-nut 20. The cover 16 may have a sound-deadening layer 22 of felt or the like.

The chamber within the annular stamping 10 25 is subdivided by an annular channel-section stamping 24 carrying a tubular air guide 26 which terminates between two cooperating stampings 28 and 30 in line with a second air guide 32 carried by stamping 30 and which is coaxially arranged 30 within a larger guide 34 carried by lower stampings 36 and 38. The bottom stamping 40 has a flange 42 for attachment to a conduit leading to the air intake of the carburetor.

The above described construction and arrangement of the parts of the air cleaner is well known, and is therefore not described in detail.

The cleaner material 14 is shown formed of a sheet 44 of thin brass, copper, or the like, having slits 46 formed in transverse series therein, so that by a stretching operation perpendicular to the plane of the sheet it may be expanded to form series of openings 48 defined by interconnected flat strands 50. As best appears in Figure 6, I prefer to roll or otherwise form the material so that the flat strands 50, instead of being perpendicular to the plane of the sheet as in most expanded sheet metal, are at an acute angle (e. g. 30°) thereto.

The sheet is then folded, as on lines 52 and 54 and as shown in Figure 4, this particular folding giving a three-ply material. As shown in Figures 5 and 6, lines 52 and 54 are so located that the openings in the various folds are out of registry, 55

thus forming tortuous passages for the incoming currents of air.

The folded material is then rolled into an annular ring, preferably of a number of thicknesses, 5 in the general form of a bandage. This ring may be distorted sufficiently to insert it by removing the cover 16 and pushing the ring of cleaner material outwardly against the cylindrical wall formed with the openings 12, between the upper 10 and lower flat annular surfaces adjacent that wall on the stampings 10 and 24. This ring, as made, is somewhat higher than the distance between the stampings 24 and 10, and is inserted under endwise (i. e. heightwise) compression. 15 Due to the inherent resilience of the expanded metal crosswise of the sheet, the ring 14 expands again heightwise after being placed in the cleaner, and yieldingly seals itself effectively against the stampings 24 and 10. Even the constant jar- 20 ring during long use in an automobile never affects or diminishes the effectiveness of this seal.

The material is kept wet with oil or the like, in the manner usual in cleaners of this type, the oil on the inclined surfaces of the interconnected 25 strands picking up the dirt from the air passing tortuously through the novel cleaner material.

As shown in Figure 7, the slits 146 may be made at an acute angle to the length of the sheet 144, in which case most of the openings 48 will be 30 out of registry in the different folds, no matter how the sheet is folded.

While one illustrative embodiment has been described in detail, it is not my intention to limit the scope of the invention to that particular embodiment, or otherwise than by the terms of the appended claims.

I claim:

1. Air cleaner material comprising a sheet of expanded metal formed as a network of interconnected strands surrounding openings in said sheet and which are of flat material arranged inclined at an acute angle to the sheet, and which is folded upon itself with the openings in one 40 ply out of registry with those in the next, so that 45 air passing therethrough is directed in a tortuous path and is forced to sweep across the surfaces of said inclined strands.

2. An air cleaner having a zone of cleaner material in the path of the air comprising a sheet of expanded metal formed and arranged to provide a series of tortuous air passages therethrough, said sheet having series of aligned openings arranged at an acute angle to the center line of the sheet, and being folded upon itself along a line perpendicular to the center of the sheet. 5

3. An air cleaner comprising a body having an air inlet and an air outlet and cleaner material 10 between said inlet and said outlet, said cleaner material comprising a sheet of expanded metal having openings therein and folded upon itself with the end portions thereof overlapping the center portion to provide at least three layers, 15 the openings in successive layers being out of register.

4. An air cleaner comprising a body having an air inlet and an air outlet and cleaner material 20 between said inlet and said outlet, said cleaner material comprising a sheet of expanded metal having parallel series of aligned openings therein at an angle to the edge of the sheet and folded upon itself along parallel lines at acute angles 25 to said series of openings with the end portions overlapping the center portion to provide at least three layers, the openings in successive layers being out of register.

5. An air cleaner comprising a casing having parts formed with upper and lower annular surfaces rigidly connected by a cylindrical wall formed with intake openings, and an annular ring of expanded metal inserted under resilient pressure heightwise of said wall over said openings and resiliently confined between said surfaces. 30 35

6. An air cleaner comprising a casing having parts formed with upper and lower annular surfaces rigidly connected by a cylindrical wall formed with intake openings, and an annular ring of a plurality of layers of expanded metal 40 arranged with the openings in said layers out of registry and inserted under resilient pressure heightwise of said wall over said openings and resiliently confined between said surfaces. 45

CLAYTON C. HARRAH.
